Attnys.

UNITED STATES PATENT OFFICE.

WRIGHT BOLTON, JR., OF NEW BEDFORD, AND NORMAN M. PAULL, OF FAIRHAVEN, MASSACHUSETTS.

CEILING ROSETTE.

Application filed November 12, 1923. Serial No. 674,122.

To all whom it may concern:

Be it known that we, WRIGHT BOLTON, Jr., and NORMAN M. PAULL, both citizens of the United States, and residents of New Bedford and Fairhaven, both county of Bristol, State of Massachusetts, respectively, have invented an Improvement in Ceiling Rosettes, of which the following description, in connection with the accompanying drawing, is a specification, like characters on the drawing representing like parts.

This invention relates to a ceiling rosette for supporting an electric lamp and the object thereof is to provide such a rosette by which the lamp may be resiliently supported to prevent vibration of the lamp and the breaking of the filament wires.

A further object of the invention is to provide a ceiling rosette from which an electric lamp may be resiliently supported by the wires which supply electricity to the lamp.

Other objects and features of the invention will more fully appear from the following description and the accompanying drawings and will be particularly pointed out in the claims.

The drawings illustrate both in section and elevation a preferred form of construction adapted for use in a ceiling rosette and embody the broad principles of the invention.

In the drawings:

Fig. 1 is a sectional view of the rosette showing in elevation an electric lamp supported therefrom;

Fig. 2 is an elevation showing the bottom of the rosette;

Fig. 3 is an elevation of the insulating sleeve.

The rosette which forms the subject matter of the present invention comprises an apertured boss 1, an insulating sleeve 2 within the aperture and resilient means 3 engaging the boss and supporting the sleeve. The electric lamp 4 is supported from the sleeve 2 by means of the wires 5 which supply electricity to the lamp.

The boss 1 is made with a flange 6 projecting therefrom by means of which the boss may be fastened to the ceiling. This flange is provided with screw openings 7 to permit the screws which fasten the rosette to the ceiling to pass through the flange.

55 The openings are preferably oval in shape

as shown in Fig. 2 in order that the screws may be placed at different distances from the center of the rosette thus insuring that the screws may be made to engage a lath in the ceiling. The aperture 8 of the boss 66 is of such a size that it will house the insulating sleeve and the resilient means which supports the sleeve and permit movement of the sleeve within the aperture.

The insulating sleeve may be made of any 65 suitable insulating material but is preferably of pressed and hardened paper. The sleeve comprises an elongated shell 9 which projects downwardly beyond the lower end of the boss to prevent chafing of the wires 70 5, and an enlarged head 10 to fit and move within the aperture. The head has a chamber 11 which communicates with the interior of the shell and within this chamber is a knot 12 formed of the twisted wires 5 which 75 convey electricity to and support the lamp. The knot is of such a size that it will lie within the chamber and will not pass therefrom into the interior of the shell. Thus the lamp is supported from the insulating 80 sleeve by means of the conducting wires which convey the electricity to the lamp. In order to prevent chafing of the wires and to prevent cutting through the insulating covering thereof, the wall of the chamber 85 slopes at 13 toward the shell so that a smooth surface is provided to contact with the wires. The sloping portion 13 may be formed integral with the head or may be a separate ring of insulating material placed 90 within the chamber after the sleeve has been made.

The resilient means 3 for supporting the insulating sleeve is preferably a helical spring surrounding the shell. In order to 95 provide bearing points for the spring, the head is formed to present a shoulder 14 on its lower side and a flange 15 projects inwardly from the wall of the aperture 8 near the lower end of the boss forming a reduced 100 orifice. The shell 9 is of a size to permit its passing through the orifice to prevent the wires 5 from rubbing against the sides of the orifice as the sleeve moves up and down to absorb vibration.

The boss is provided with openings 16 to 105 permit the passage of the upper ends of the wires 5 from the knot 12 to metallic contact plates 17 held on the under side of the flange 6 by the usual screws 18. The con-

tact plates are provided with the usual screws 19 for connecting the ends of the wires 5 to the contact plate and screws 20 for connecting the line wires (not shown) 5 to the contact plates. To permit the passage of the wires 5 from the knot 12 to the opening 16, a space 21 is provided in the upper part of the rosette and to prevent chafing of the wires against the upper part 10 of the head 10 openings 22 are formed in the wall of the head so that when the sleeve moves the upper edge of said wall is permitted to pass above the wires.

From the above description it will be 15 seen that with the rosette shown it is unnecessary to provide any fixture to support the lamp and the lamp is resiliently supported by the wires which convey the electricity from the line wires to the lamp. 20 All the parts of the rosette are cheap and easy to manufacture and the entire device is of extremely simple construction and may be easily assembled. The rosette is designed to take the place of the usual non-resilient 25 rosette from which electric lamps are now supported and therefore is preferably made to have such proportions and have the openings, particularly the openings 7, so positioned that the rosette may be used in the 30 places from which the non-resilient rosettes are removed. The proportions of the device may be changed and it is obvious that other modifications may be made and it is, therefore, desired that the invention be construed as broadly as the limitations in the 35

claims, taken in conjunction with the prior art, may allow.

Having thus described the invention what is claimed as new and desired to be secured by Letters Patent is:

In an electric light fixture, the combination with an electric lamp of a ceiling rosette comprising a depending apertured boss, a flange projecting inwardly from the wall of the aperture near the lower end of the boss forming a reduced orifice, an insulating sleeve within the aperture having an elongated shell formed of light material and of uniform diameter to permit its passing through said orifice and an enlarged head 40 forming a part of the shell and adapted to fit and move within the aperture, said head having a chamber communicating with the interior of the shell and presenting a shoulder on its lower side, a coiled spring surrounding said shell and bearing at one end against the flange and at the other end against the shoulder resiliently to support the sleeve, and conducting wires for conveying electric current to the lamp, said wires being fastened to the lamp to support the lamp and twisted to form a knot of a size to lie and be retained within the chamber of the head 45 whereby the lamp is resiliently supported by the wires.

In testimony whereof, we have signed our names to this specification.

WRIGHT BOLTON, JR.
NORMAN M. PAULL.
